UNITED STATES PATENT OFFICE.

JOHN P. LAIRD, OF ALTOONA, PENNSYLVANIA.

IMPROVEMENT IN FIRE-BOXES OF LOCOMOTIVES.

Specification forming part of Letters Patent No. 40,630, dated November 17, 1863.

To all whom it may concern:

Be it known that I, JOHN P. LAIRD, of Altoona, Blair county, Pennsylvania, have invented an Improvement in the Fire-Boxes of Locomotive-Boilers; and I do hereby declare the following to be a full, clear, and exact description of the same, reference being had to the accompanying drawings, and to the letters of reference marked thereon.

My invention consists of certain tubes arranged within the fire-box of a locomotive-boiler, substantially as described hereinafter, so as to serve as an efficient support for a partition of fire-clay or other refractory material, which, as hitherto supported in the fire-boxes of locomotives, has been liable to become loose and drop onto the fuel, the said tubes at the same time adding to the heating surface and capacity of the boiler.

In order to enable others to carry out my invention, I will now proceed to describe the manner of constructing the same.

On reference to the accompanying drawings, which form a part of this specification, Figure 1 is a vertical section of sufficient of a locomotive-boiler to illustrate my invention; and Fig. 2 a transverse section on the line 1-2, Fig. 1.

A represents the top of the boiler above the fire-box; B, the front of the boiler; C, the roof of the fire-box; D, the front of the same; E, the rear plate of the fire-box or tube plate; F, the opening for the admission of the fuel, and G the grate. H H are tubes, each of which is bent abruptly at h, one end being secured to the roof C of the fire-box and the other end to the tube-plate E. These tubes are arranged at a suitable distance apart from each other, as seen in Fig. 2, and occupy within the fire-box the inclined position shown in Fig. 1. On the top of the inclined portion of the tubes H rest the tiles I, of fire-brick, or other material capable of resisting the action of the fire, these tiles being arranged in as many pieces or sections as may be deemed convenient.

It has been found in practice that a fire-clay partition arranged within the fire-box of a locomotive-boiler in the inclined position illustrated in Fig. 1, tending as it does to direct the products of combustion from the rear to the front of the fire-box, has the effect of causing the smoke and gases to be consumed, especially when there are openings x at the rear of the fire-box for the admission of small jets of air to a point a short distance below the partition. Great difficulty has, however, been experienced in maintaining these partitions of friable material entire, the motion of the locomotive tending to break and displace the slabs or tiles. It will be seen that the tubes H overcome this defect, as they form a firm and indestructible foundation on which the tiles rest, at the same time the tubes add to the heating surface and capacity of the boiler, and afford a medium for the free circulation of water in the neighborhood of the fire-box.

I am aware that the use of tubes for supporting combustion-chambers in fire-boxes has been proposed. I therefore do not desire to claim, broadly, the use of tubes for supporting fire-clay bricks or tiles in the fire-boxes of locomotives, nor do I claim, broadly, the fire-clay partition I; but

I limit my claim to, and desire to secure Letters Patent for—

The within-described arrangement of tubes H, passing from the rear plate or tube-sheet to the crown, for the purpose of sustaining the partition I, of fire-clay or other refractory material, within the fire-box of a locomotive-boiler, in the manner herein set forth.

In testimony whereof I have signed my name to this specification in the presence of two subscribing witnesses.

JOHN P. LAIRD.
